UNITED STATES PATENT OFFICE.

FRANK OLIVER FRENCH, OF ST. JOHNSBURY, VERMONT, ASSIGNOR TO THE
E. & T. FAIRBANKS & CO., OF SAME PLACE.

DESIGN FOR A SCALE-BEARING.

SPECIFICATION forming part of Design No. 34,536, dated May 21, 1901.

Application filed April 8, 1901. Serial No. 54,952. Term of patent 14 years.

To all whom it may concern:

Be it known that I, FRANK OLIVER FRENCH, a citizen of the United States, residing at St. Johnsbury, in the county of Caledonia, State 5 of Vermont, have invented a certain new and original Design for Scale-Bearings, of which the following is a description, reference being had to the accompanying drawings and to the letters of reference marked thereon.

10 My invention relates to a new and original design for a scale-bearing; and it consists in a scale-bearing member of the shape and configuration as hereinafter described.

15 In the drawings, Figure 1 is a front view of a scale-bearing embodying my invention. Fig. 2 is a plan view of the same, a portion being shown in dotted lines.

In the drawings, *a* represents the top, *b* the post, and *c* the base, of the scale-bearing mem-

ber. The top *a* is rectangular in shape. The 20 post *c* is also rectangular, but arranged at an angle to the top part. The web *d* of the post *b* is placed parallel with the sides of the top *a*, while the flanges *e* are set over, forming a section similar to a **Z**-bar. 30

The leading feature of the design consists of a bearing member of the shape and configuration herein shown and described.

I claim—

10 The design for a scale-bearing, substantially as shown and described.

In testimony whereof I affix my signature in presence of two witnesses.

FRANK OLIVER FRENCH.
